UNITED STATES PATENT OFFICE.

EDMUND C. MORGAN, OF NEW YORK, N. Y.; OLIVE EUGENIE MORGAN EXECUTRIX OF
SAID EDMUND C. MORGAN, DECEASED.

SHOVELING MACHINE.

Application filed December 19, 1917, Serial No. 207,867. Renewed October 19, 1925.

This invention relates to a machine for loading coal and other material, and has for its object the provision of a device of the class named which shall be of improved construction and operation.

The invention is exemplified in the combination and arrangement of parts shown in the accompanying drawings and described in the following specification, and it is more particularly pointed out in the appended claims.

In the drawings—

Fig. 1 is a side elevation of a machine embodying one form of the present invention.

Figs. 3, 4 and 5 together constitute a side elevation of the machine shown in Fig. 1, but on a larger scale.

Figs. 6, 7 and 8 together constitute a top plan view of the machine shown in Figs. 3, 4 and 5.

Figs. 9 and 10 together constitute a fragmentary longitudinal sectional view of the machine.

Fig. 11 is a horizontal sectional view of the central portion of the machine taken on a plane just above the truck wheels.

Fig. 12 is a vertical sectional view on line 12—12 of Fig. 9.

Fig. 13 is a vertical sectional view on line 13—13 of Fig. 5.

Fig. 14 is a vertical sectional view on line 14—14 of Fig. 3.

Fig. 15 is a top plan view of a modified form of shovel which may be used in connection with the invention.

Fig. 16 is a vertical sectional view with parts shown in full of the shovel illustrated in Fig. 15.

Fig. 17 is a side elevation of the shovel shown in Fig. 15.

Fig. 18 is a fragmentary side elevation of a portion of the operating mechanism looking at the opposite side from that shown in Fig. 17; and

Fig. 19 is a vertical sectional view on line 19—19 of Fig. 17.

The embodiment of the invention shown in the drawings comprises a machine supported by truck wheels designated by the numeral 20, which are secured to axles 21, journaled in bearings 22 formed in a main frame plate 23. The plate 23, as shown in

Figs. 3, 4 and 5, extends for a considerable distance in the front and rear of the truck wheels 20, and as shown in Fig. 9, is reinforced by longitudinally extending ribs 24. Mounted on the plate 23, as shown best in Fig. 11, is a motor 25 which drives a worm 26 through reduction gearing carried in a gear casing 27. The worm 26 meshes with a worm wheel 28 and is provided with a number of worm threads so that the pitch of the threads is sufficiently steep to permit of backward driving of the worm wheel and worm. The worm wheel 28 is mounted on a shaft 29, which is journaled in a side bracket 30 secured to the frame plate 23. The shaft 29 is connected with the axles 21 of the truck wheels 20 by means of beveled gears 31. Brake shoes 32 are supported by links 33 in position to bear upon the wheels 20 and are moved into and out of contact with the truck wheels by means of links 34 and a lever 35 which is held in adjusted positions by a tooth segment 36. The lever 35 is connected with a shaft 37 which extends across the frame 23 to operate the brakes on opposite sides of the truck.

The frame plate 23 is provided near its center with a main pivot pin 40, by means of which a forward supplemental frame 41 and a rear discharge conveyer frame 42 are connected with the truck. The frames 41 and 42 are provided with an upper pivotal connection 43 which is secured to the conveyer frame 42 by a yoke 44 and to the supplemental frame 41 by a yoke 45 and adjustable screw rods 46. By this arrangement the supplemental frame 41 and the conveyer frame 42 may be independently swung laterally upon the main frame plate 23, and also relative to one another. The discharge conveyer frame 42 is provided with a hopper 47 which converges toward the rear, as shown in Figs. 6 and 7, to form the sides of the conveyer frame. The rear portion of the conveyer frame is provided with movable side boards 48 hinged to the main portion of the frame at 49 and having a locking mechanism 50 for holding them in upright position. Similar side boards 51 are provided for the converging walls of the hopper portion 47. The side boards 48 and 51 may be folded inwardly to permit the machine to travel through low places in the mine chamber. The rear end of the frame plate 23 is provided with a curved I-beam 52 which

forms a sliding support for the conveyer frame 42. The upper bar of the I-beam 52 fits in a slot 53 formed in a horizontally extending plate 55 secured to the conveyer frame 42 by upright plates 56. An endless conveyer 57 is arranged to travel over a bed plate 58, as shown in Fig. 14, the bed plate being supported at its outer edges by the side walls of the frame 42 and being bent over, as shown at 59, to cover the chains of the conveyer. Angle bars 60 may be provided for guiding the conveyer upon the bed plate 58. The conveyer is driven by a motor 61 mounted on the plate 55, and driving a shaft 62 which carries sprocket wheels 63, over which the conveyer 57 passes. Secured to pins 64, adjacent the rear end of the frame plate 23, as shown in Figs. 3 and 14, there is provided a pair of segmental shoes 65 which have a detachable pivotal connection with the main plate 23. The shoes 65 on one side of their pivot pins 64 are shaped to bear upon the track rails 66 having their outer periphery arranged to form an arc which will rest upon the rails, although the shoes may be tilted to different angles about their pivot pins. The sides of the shoes, opposite the pins 64, are provided with ears 67 to which screw rods 68 are fastened by means of pins 69. The rods 68 at their outer ends carry pointed contact members 69' which may be forced outwardly along the rods 68 by threaded hand wheels 70. The contact members 69' may be forced into engagement with the roof of a mine chamber to hold the frame of the machine rigidly in position upon the track 66, and when this is done, the shoes 65 bear upon the track to take the downward thrust of the rods 68, and thus prevent tilting of the frame of the machine. It is apparent that the rods 68 may be swung laterally to engage the sides of the mine chamber, or may be inclined downwardly, or adjusted to a variety of positions in order to secure proper anchoring of the machine frame. The conveyer 57 may discharge its material into a car 71 shown in broken lines in Fig. 3, or it may be swung to one side of the track to discharge material into the gob in case material is encountered which is not of sufficient value to justify its removal from the mine. A controller 72 is located adjacent the rear end of the conveyer frame 42 and is connected with the motor 61, by which the conveyer 57 is driven so that the movement of the conveyer may be controlled from the car 71.

The supplemental frame 41 is provided with a rearwardly extending arm 73 which connects the frame with the pivot pin 40 and which is bowed upwardly, as shown in Fig. 9, to clear the bearing 22 for the front truck axle. The frame is provided with a rear wall 74 and side walls 75 which extend forwardly a considerable distance beyond the front end of the base plate 73. The bottom

plate 76 of the frame 41 extends forwardly a greater distance than the main portion of the side walls 75 and to a position near the front end of the machine. The walls 75, adjacent their base, are offset outwardly, as shown at 77 in Figs. 4, 5 and 12, to form a slideway for rack bars 78, the purpose of which will be explained later. As shown in Figs. 5 and 8, the main portions of the side walls 75 are discontinued some distance in the rear of the front end of the machine, but the slideway 77 and their racks 78 extend a considerable distance in front of the forward end of the main portions of the side walls. The supplemental frame 41 supports an inclined extensible conveyer 79 which is provided with main side walls 80 which are fixed in position, and which rest, as shown in Figs. 9 and 10, at their rear ends upon the upper edge of the rear wall 74 of the frame 41, and at 85 their forward end upon the front end of the floor plate 76. The side walls 80 are connected by a conveyer bed plate 81 which is located a slight distance above the lower edges of the side walls, and a short bed plate 82 connects the lower edges of the side walls 81 near their front ends. A pair of conveyer chains 83, connected by flights 84, constitute a conveyer, one run of which travels upwardly over the bed plate 81, while the return run is supported at the forward end of the conveyer by the short plate 82. The unsupported portion of the conveyer, in the rear of the plate 82, engages sprocket wheels 85, carried by a shaft 86, and driven by a motor 87, which is mounted upon the rear wall 74 of the frame 41. The upper portions of the walls 80, as shown in Figs. 9 and 12, are provided with hinged extensions 88 having a latch 89, Fig. 4, for holding them in upright position and arranged to be folded inwardly to permit the machine to move beneath a low roof.

As shown in Fig. 12, the bed plate 81 is bent to form inwardly projecting flanges 90, upon which sliding shoes 91 are supported, and along which they are free to move in the longitudinal direction of the conveyer. The shoes 91 are connected by a shaft 92, which supports a sleeve 93 formed at the upper end of a supplemental conveyer bed plate 94. The bed plate 94 is connected at its lateral edges with side walls 95, which cooperate with the bed plate 94 to form a supplemental conveyer frame, supported at its rear end by the shoes 91, and slideable longitudinally along the supporting flanges 90. The forward end of the supplemental conveyer frame is connected by means of a shaft 96, as shown in Figs. 8 and 10, with inwardly projecting lugs 97 formed on the inner faces of the rack bars 78. The forward end of the bed plate 94 is formed into a sleeve 98 over which the return run of the conveyer chains 83 are guided after they 130

have passed over the bed plate 82. In this way the conveyer is directed onto the upper surface of the bed plate 94. After the conveyer passes around pulleys 99 and the sleeve 95 at the upper end of the bed plate 94, it returns in an idle run to the lower end of the stationary conveyer frame where it is guided around pulleys 100 on a fixed shaft 101. By this arrangement both of the active runs of the conveyer which travel upon the upper surfaces of the bed plates 81 and 94, move upwardly when the sprocket wheels 85 are rotated in a clockwise direction, as viewed in Fig. 9. This will cause material on the bed plate 94 to be carried to the upper end of this plate and discharged onto the bed plate 81, along which it continues to move upwardly until it is discharged into the hopper 47. Since the shaft 96 at the forward end of the supplemental bed plate 94 is connected with the rack bars 78, forward movement of these bars in their slide-ways 77 will carry the front end of the supplemental conveyer forwardly and cause the rear end supported by the shoes 91 to slide forwardly and downwardly along their supporting flanges. Such forward movement of the supplemental conveyer will not alter the length of chain required, since the rear end of the supplemental conveyer moves forwardly at the same rate as the front end.

The rack bars 78 are slid back and forth in their guideways by means of pinions 102, secured to a shaft 103, which is rotatably mounted in extensions 104 projecting forwardly from the supplemental frame 41. The outer end of the shaft 103 carries a beveled gear 105, which meshes with a beveled gear 106, secured to a shaft 107, which is journaled in bearings 108 projecting from the outer face of one of the offset portions 77 of the side walls 75. The shaft 107 carries at its rear end a worm wheel 109, which meshes with a worm 110 on a shaft 111 projecting through an opening in the side walls 75. The shaft 111 is driven by a motor 112 secured to the floor plate 76 of the frame 41. A second motor 113 is also mounted on the floor plate 76 of the supplemental frame, and is geared to a worm 114, meshing with a worm wheel 115, Figs. 9 and 12, which is secured to the upper end of a shaft 116, journaled in a bearing 117, and carrying a spur gear 118 at its lower end beneath the floor plate 76. The gear 118 meshes with rack teeth 119 formed on the front edge of the main frame plate 23. When the motor 113 is driven the gear 118 and the shaft 116 will travel along the rack 119, and thus shift the supplemental frame 41, together with all the parts mounted upon it, laterally about the pivot as an axis. The worm gears 114 and 115 are preferably of the self-locking type, so that the supplemental frame 41 will be held in any position to which it is moved by rotation of this gearing. During this shifting movement the floor plate 76 slides upon the upper surface of the main frame plate 23. The motors for driving the various parts of the machine, with the exception of the rear conveyer, are connected with a series of controllers 120 mounted on one of the side plates 75 of the supplemental frame. A runner-board 121 is hinged to the base plate 23 adjacent the controllers for the mo-

70
75
75

by rotation of this gearing. During this shifting movement the floor plate 76 slides upon the upper surface of the main frame plate 23. The motors for driving the various parts of the machine, with the exception of the rear conveyer, are connected with a series of controllers 120 mounted on one of the side plates 75 of the supplemental frame. A runner-board 121 is hinged to the base plate 23 adjacent the controllers for the mo-

125

As shown in Figs. 5, 8, 10 and 13, a shaft 122 is journaled in the rack bars 78 near their forward ends and extends transversely of the machine from one of the rack bars to the other. The bearings for the shaft 122 are extended by means of bosses 123 on the inner faces of the bars, and adjacent these bosses is a pair of sleeves 124 keyed to the shaft. As shown best in Fig. 10, the sleeves 124 are provided with arms 125 which extend forwardly from the shaft 122 and support a scoop 126 rigidly upon the shaft for vertical movement about the axis of the shaft whenever the shaft is rotated. As shown in Fig. 8, the rear portion of the scoop corresponds in width to the width of the front end of the conveyer connected with the shaft 96 supported by the rack bars. The front end of the scoop is flared laterally so that its forward edge is longer than the width of the conveyer, and this edge is provided with a series of teeth 127 for engaging the material to be loaded. The scoop 126 is swung upon its pivotal support by means of a worm wheel segment 128 keyed to the shaft 122 and meshing with a worm 129, journaled in a bearing 130, which is formed integral with a gear casing 131. The gear casing 131 is supported upon the frame of a motor 132, by means of which motor the gearing within the casing is driven. The motor 132 is carried upon a platform 133, which in turn is supported by a standard or bracket 134 projecting upwardly from the rack bars 78 and secured rigidly thereto. The bracket 134 is so positioned relative to the rack bars that when the bars slide along their guideways 77, the bracket will move along the inner face of the guideway 77 adjacent that portion of the guideway which extends in front of the main portion of the side walls 75. The worm wheel and worm 128 and 129 are preferably of the self-locking type, so that the shovel 126 will be held in whatever angular position it is caused to assume. Worm gearing for tilting the shovel 126 will enable the latter to be moved up very powerfully which is particularly desirable when coal is to be loosened preparatory to loading; furthermore, the worm gearing enables the scoop to be lowered positively and therefore prevents it from being dropped by gravity.

In order to counterbalance the weight of

- the scoop 126, the shaft 122, at the end opposite the worm segment 128, is provided with a crank arm 135, which is rigidly secured to the shaft, and is connected at its 5 outer end to a rod 136, secured to a counter-balancing spring within a tubular casing 137, as shown best in Figs. 5 and 8. The rear end of the spring casing 137 is pivotally connected to a standard 138 projecting 10 upwardly from one of the racks 78 and arranged to move with the rack along the inner face of its guideway 77 in a manner similar to the support for the motor 132. It will be noted that the spring counterbalance 15 always acts in an upward direction upon the scoop 126 and that the bar 136 is above the pivotal axis of the scoop, even when the scoop is in its lowermost position, as shown in Fig. 5.
- 20 The racks 78 at their forward ends are provided with screw jacks 139, which may be adjusted by hand wheels 140 to regulate the distance of their foot plates 141 above the surface of the mine floor. Since the 25 scoop 126 is located at a considerable distance in front of the supporting truck, it will be apparent that when the scoop is tilted about its axis to lift material, there will be a tendency for the front end of the machine 30 on which the scoop is supported to tilt downwardly. This will be especially true when the racks 78 are extended to a position in advance of the front end of the supporting frame. Any downward movement 35 of the scoop, due either to a tilting of the entire machine caused by the load upon the scoop, or to a springing of the supporting frame produced by the same cause, is arrested by the jacks 139 which come into contact 40 with the floor of the mine chamber before the downward movement of the scoop is sufficient to interfere with the operation of the machine. The jacks will continue to support the scoop so long as the weight is 45 sufficient to cause them to engage the mine floor, and if it is desirable to move the scoop laterally or longitudinally at such times, the jacks may be caused to slide upon the surface of the floor a sufficient amount 50 to permit such movement. As soon as the weight upon the scoop is removed, the frame will return to its original position and thus raise the jacks away from the floor.
- In operation, the shoveling machine is 55 transported along the track in the mine chamber until its forward end is brought adjacent the material to be loaded which has been previously loosened by any of the well-known methods employed for this purpose.
- 60 The truck and main frame of the machine is then anchored in this position by means of the braking mechanism and the anchoring jacks 68 previously described. The shovel 126 is then tilted about its axis 122 65 into proper position to engage the material, and the conveyer 83 is set into operation by means of the motor 87. The rack bars 78 are then driven forwardly to force the nose of the scoop 126 into the material to be loaded, and when the scoop has been filled it is tilted about its axis 122 by means of the worm wheel segment 128 and caused to dump from its rear end onto the conveyer 83. It should be noted that the supplemental sliding frame for the conveyer 83 maintains the front portion of the conveyer in position to receive material from the scoop 126 independently of the position of the scoop relative to the frame of the machine. In other words, the scoop may be dumped when it is extended to its extreme forward position by the rack bars 78, or when it is in its rearmost position, or at any position intermediate the two. The extensible conveyer 83 will carry the material backwardly and discharge it 70 into the hopper 47 no matter in what position the scoop happens to be at the time it is dumped. The scoop may, therefore, be pushed forwardly a sufficient amount to fill the scoop, and the material thus gathered 75 may be dumped and the scoop lowered for a second filling without being retracted. The scoop may also be swung laterally about the pivot 40 to gather material at the sides of the mine track in a wide chamber, and 80 the parts will operate in the same manner as they do when the scoop is directly in front of the machine.
- In the modified construction shown in 85 Figs. 15 to 19, inclusive, the scoop 142 is not usually swung upwardly to dump its contents onto the conveyer, but instead the conveyer chains 83 are extended forwardly 90 around a shaft 143 located in the nose 144 of the scoop. The scoop is pivotally supported by bearing lugs 145 and 146 carried by the rack bars 78, and a worm gear segment 147 is connected with the pivot pin 95 extending through the lug 146. This segment is rigidly connected with the scoop by 100 means of the pivot pin and engages a worm 148, by means of which the scoop may be 105 swung upwardly to dumping position or to hold it in position to clear the track when the machine is being transported from one 110 position to another. The worm gearing 147, 148 may be made of the non-self-locking type when it is desired that the scoop 142 shall have freedom of movement up and 115 down about its pivotal support while moving over an irregular floor and the beveled nose 144 alone relied on to keep the material in contact with the floor and preventing it from riding up on the material. When the floor is substantially horizontal, however, the 120 worm gearing 147, 148 may be made of the self-locking type so as to hold the scoop down in adjusted position and assist the beveled nose 144 in keeping the scoop in contact 125 with the floor during the loading operations.

The self-locking type of worm gearing will also enable the scoop to be held at adjusted elevation when it is retracted with the load while the conveyer is transferring the material toward loading position. Whether the worm gearing 147, 148 is of the non-self-locking type or of the self-locking type it will enable the scoop to be positively lowered and prevent it from being dropped by gravity. The worm is driven by a motor 149 carried upon the rack bars 78 in a manner similar to that described in connection with the form of the invention previously discussed. At the side of the scoop, opposite the worm segment 147, a crank arm 150 is secured to the pivot pin passing through the bearing lug 145, and the arm 150 has its outer end connected to the end of a counterbalance rod 151, similar to the counterbalance previously described. It will be seen from Fig. 17 that this form of the invention differs from the other form in that the crank 150 is below its dead center when the scoop 142 is in its lowermost position. By this means the counterbalance tends to hold the scoop in its operating position after it has been swung downwardly to rest upon the floor of the mine chamber. If it is found desirable, a supplementary locking pin 152 may be provided to lock the scoop in this position, but ordinarily the locking action of the counterbalancing spring will be sufficient for this purpose. The scoop 142 is provided with side walls 153 which overlap the walls 95 of the sliding conveyer frame so as to confine the material carried rearwardly by the conveyer.

In operating this form of the invention the machine frame is anchored in position in the mine chamber in the manner previously described and the scoop is carried forwardly by the rack bars 78 to force the nose-piece beneath the loosened material to be loaded. As the scoop enters the material, the material is deposited directly on the conveyer and carried rearwardly toward the car into which it is to be loaded, and there is no necessity for raising the scoop as in the form previously described but such lifting of the scoop may be effected whenever desired. The machine may be operated to gather material at either side of the track in the same way as the other form of the invention.

I claim:

- 55 1. In loading apparatus, the combination with a main frame, of a supplemental frame, a scoop connected to said supplemental frame, means for moving said supplemental frame to cause said scoop to gather a load, and an endless conveyor mounted on said main and supplemental frames with a receiving portion continually in position to receive material from said scoop, and a delivery portion on each of said frames.
- 56 2. In loading apparatus, the combination

with a supporting frame, of auxiliary supporting mechanism extensible relatively to said supporting frame, a chute pivotally connected to said extensible supporting mechanism with its rear portion slidable along 70 said supporting frame, a scoop connected to said extensible supporting mechanism, means for actuating said extensible supporting mechanism to cause said scoop to gather a load of material, and an extensible conveyer 75 having an upper rearwardly extending loop on said chute for delivering material to a lower loop on said supporting frame.

3. In loading apparatus, the combination with a supporting frame having wheels 80 adapted for transportation of a machine on a mine track, of shoveling mechanism mounted on said frame for forward and rearward movements rectilinearly relatively thereto, means for anchoring said frame to 85 the rails of said track independently of said wheels to form a rigid abutment to resist the tendency of said frame to move along said track during the operation of said shoveling mechanism, and self-contained 90 power-operated means for operating said shoveling mechanism by forward and rearward rectilinear movements thereof relatively to said frame while the latter is thus anchored to the rails. 95

4. In loading apparatus, the combination with supporting framework having an extensible portion mounted thereon, of a scoop connected to said extensible portion and movable bodily therewith, means for moving 100 said extensible portion forward to cause the scoop to gather a load, and extensible conveyor mechanism having superposed loops in position to receive material from said scoop and transfer such material from 105 one loop to the other and thence to loading position.

5. In a loading machine, the combination with a supporting frame adapted to occupy a stationary position, of extensible supporting mechanism connected to said frame, a scoop mounted on said extensible supporting mechanism with a space in advance thereof free and unobstructed, means for moving said extensible supporting mechanism to cause said scoop to reach out from 110 said supporting frame to gather a load, endless conveyer mechanism connected between said supporting frame and said scoop in position to receive gathered material to transfer the same toward loading position, and self-contained power-operated mechanism for tilting said scoop relatively to said extensible supporting mechanism. 115

6. In a loading machine, the combination with a supporting frame, of anchoring mechanism for said supporting frame to hold the same stationary, extensible supporting mechanism mounted on said supporting frame, a scoop connected to said extensible support- 120

125

- ing mechanism, means for moving said extensible supporting mechanism to advance said scoop relatively to said supporting frame along horizontal lines while said supporting frame remains anchored, extensible conveyer mechanism continuously connected between said scoop and said supporting frame during the forward movement of said extensible supporting mechanism, means for operating said extensible conveyer to carry material from the outer end of said scoop toward loading position during the operation of said scoop to gather a load, and self-contained power-operated mechanism for tilting said scoop.
7. In a loading machine, the combination with a supporting frame, of a scoop having a forward portion extending rearwardly in an approximately horizontal plane from the forward receiving end of said scoop, means for advancing and retracting said scoop along horizontal lines substantially parallel to the forward horizontal bottom of said scoop, an endless conveyer extending along such bottom of said scoop from the outer end thereof to receive all of the material collected by said scoop, means for supporting said conveyer to permit extension thereof with said scoop during advance movement of the latter, and means for operating said conveyer during the forward movement of said scoop to transfer material from the latter along said supporting frame to a predetermined loading position.
8. In loading apparatus, the combination with a supporting frame, of a supplemental frame comprising an inclined chute, an auxiliary frame for pivotally supporting the forward end of said chute, a scoop pivoted at its rear end to said auxiliary frame in fixed relation to the forward pivoted end of said chute, an extensible endless conveyor mounted on said main and supplemental frames in position to travel rearwardly along said chute from a receiving position at the forward pivoted end of said chute and adjacent the rear pivoted end of said scoop, means for moving said auxiliary frame forward to cause said scoop to gather a load while said chute is moved forward with said auxiliary frame and said conveyor is extended to maintain the said receiving end of said conveyor adjacent the rear end of said scoop in position to receive material from the latter in any of the forward positions of said auxiliary frame, and means for tilting said scoop in any of its positions forward of the main frame for delivering material to said conveyor.
9. In a loading machine, the combination with a supporting frame, of a scoop having a turning axis at its rear end confined to a generally horizontal path of movement, an extensible conveyor behind said scoop with a portion thereof always in a receiving

position, means for moving the scoop bodily forward and rearward parallel to the length of the machine and relatively to said frame to secure a load, and mechanism for swinging the front portion of said scoop on such axis substantially at the rear portion of said scoop to deliver its load rearwardly to said conveyor in any of the forward positions of said scoop.

10. In a loading machine, the combination with a supporting frame, of a scoop having a turning axis confined to a generally horizontal path of movement, extensible conveyor mechanism behind said scoop, driving mechanism for moving said scoop forward and rearward relatively to said frame to reach out for a load while the receiving portion of said conveyor remains adjacent the said scoop, and means for turning said scoop on such axis to discharge material from said scoop onto said conveyor in various positions of said scoop relative to said supporting frame.

11. In a loading machine, the combination with a frame, of a scoop having a turning axis confined to a generally horizontal path of movement, conveyor mechanism mounted on said frame and extended to a receiving position horizontally back of said scoop with the receiving portion thereof movable horizontally along such restricted path to be constantly in receiving communication with said scoop, and means for effecting forward and backward reciprocating horizontal movements of the rear portion of said scoop and also tilting movements thereof, whereby such reciprocating and tilting movements cooperate to enable said scoop to take a load and discharge it onto said extensible conveyor mechanism.

12. In a loading machine, the combination with guideways extending forward and rearward, of an endless extensible conveyor with the forward receiving portion thereof between said guideways, supporting mechanism confined in said guideways, a scoop pivotally connected at its rear end directly to said supporting mechanism in fixed relation to the receiving end of said conveyor, means for effecting the movement of said supporting mechanism backward and forward together with the receiving end of said conveyor and the rear end of said scoop to effect the operation of said scoop and the maintenance thereof in predetermined relation to the conveyor and means for operating said conveyor to transfer toward loading position material received from said scoop during any of the advanced positions thereof.

13. In a loading machine, the combination with a main frame, of a supplemental frame movably mounted on said main frame, a scoop connected to said supplemental frame, worm gear mechanism directly connected to

- 5 said scoop for elevating the forward end thereof, means for moving said scoop forward to gather a load, and extensible conveyer mechanism mounted on said main and supplemental frames with a receiving portion always in receiving position relative to said scoop.
- 10 14. In a loading machine, the combination with a narrow elongated truck frame mounted on wheels adapted to travel on a main track in a mine, of abutment mechanism adapted to rigidly connect said frame to the rails of said track and to the interior of the mine chamber independently of said wheels,
- 15 a supplemental frame movably mounted on said main frame, an endless conveyer traveling from a receiving position at the forward end of said supplemental frame to a delivery position at the rear end of said truck frame,
- 20 a scoop pivoted to the forward end of said supplemental frame and having a flat bottom adapted to rest on the floor in advance of the mine track and slide thereover, and propelling mechanism independent of said
- 25 wheels for moving said scoop forward to gather a load against the resistance of said abutment mechanism and while said conveyer remains in position throughout its length for transferring gathered material
- 30 toward loading position.
15. In a loading machine, the combination with supporting framework, of conveyor mechanism extending from the forward end of said framework longitudinally thereof toward the rear, a scoop open at both ends and pivotally mounted at the forward end of said framework in advance of said conveyor mechanism and in alinement therewith and pivoted at its rear portion for operation in a low-roof mine chamber, worm gear mechanism connected directly to said scoop at its pivot, means for moving said scoop forward to take a load, and means for actuating said worm gearing to tilt said scoop to discharge the load therein out of the rear end thereof onto said conveyor mechanism.
- 35 16. In a loading machine, the combination with a supporting frame, of a supplemental frame mounted on said supporting frame for arcuate movement on an upright axis relatively thereto, extensible conveyer mechanism mounted on said frames, a scoop in registry with the receiving end of said conveyer mechanism and extending in advance thereof in its various arcuate positions, a pivotal connection between said scoop and said supplemental frame, mechanism for confining the turning axis of said scoop to a generally horizontal path of movement, means for operating said conveyer, and means for operating said scoop to deliver material to said conveyer in the various positions of said supplemental frame and in the various advanced positions of said scoop.
- 40 17. In a loading machine, the combination with a supporting frame, of guide-ways extending forward and rearward of said frame, slide-blocks confined in said guide-ways, conveyor mechanism on said frame behind said blocks, a scoop pivoted directly to said slide-blocks rearward of its front portion and mechanism comprising a worm gear rigidly connected to said scoop for turning the latter in said blocks to discharge material out of the rear end thereof by gravity onto said conveyor mechanism.
- 45 18. In loading apparatus, the combination with a portable truck having wheels adapted to travel on a mine track, of power mechanism for propelling said truck forward, a conveyor mounted on said truck and extended from the front toward the rear, a scoop for delivering material to said conveyor from a position forward of said truck, mine jack mechanism adapted to rigidly connect the truck frame to the rails of the mine track and to the roof of the mine chamber independently of said wheels to act as a rigid abutment against rearward movement of said truck frame along said track, and additional propelling mechanism for said scoop to move the same forward more powerfully than said first-named mechanism to effect forcible movement of said scoop into a pile of material or under material in a pile.
- 50 19. In a loading machine, the combination with supporting framework, of a pair of arms slidably mounted on said framework, a scoop pivotally connected to said arms, means for advancing said arms relatively to said supporting framework to cause said scoop to gather a load, means comprising worm gearing connected directly to said scoop at its pivotal connection with said arms and movable with the latter for swinging said scoop about its pivotal support at various positions of adjustment thereof to discharge material from said scoop, and conveyor mechanism mounted on said framework to travel to and from a position for receiving material from said scoop when the latter is tilted upwardly about its pivotal support.
- 55 20. A loading machine comprising a frame, a pair of arms slidably mounted on said frame, rack and pinion mechanism for advancing said arms relative to said frame, a scoop pivotally mounted on said arms adjacent the forward end thereof, a motor carried by one of said arms for swinging said scoop about its pivotal support, and a conveyor having an extensible portion connected with said arms adjacent the pivotal support for said scoop for receiving material from said scoop.
- 60 21. In loading apparatus, the combination with a wheel-mounted vehicle, of propelling mechanism for transporting the same forwardly and rearwardly, an endless belt
- 65 120 125 130

- conveyor mounted on said vehicle and extending from a low position at the front end of said vehicle on an incline longitudinally to a higher position toward the rear of said vehicle, a scoop mounted on said vehicle in advance of said conveyor and in registry therewith for delivery of material to said conveyor, spaced apart roof jacks each pivotally connected to the frame of said vehicle 10 in position to engage the respective rails of said track for anchoring said vehicle against movement thereof in either direction along said track, and for moving said scoop forward more powerfully than said first-named propelling mechanism to force said scoop under material to obtain a load while said roof jacks act as rig'd abutment mechanism.
22. In loading apparatus, the combination with a frame, of a scoop having a turning axis at its rear end confined to a generally horizontal path of movement, a conveyor on said frame behind said scoop, means for moving the scoop bodily forward and rearward parallel to the length of the machine and relatively to said frame to gather a load, mechanism for swinging the front portion of said scoop on such axis at the rear portion of said scoop to deliver its load rearwardly to said conveyor, and counter-balancing mechanism for said scoop.
23. In a loading machine, the combination with a supporting frame, of a scoop pivotally connected at its rear portion to said frame, mechanism comprising worm gearing connected to said scoop for tilting the same to discharge material out of the rear end thereof, means for advancing said scoop relatively to said frame to cause said scoop to gather a load while the pivotal axis of said scoop is confined to movements along approximately horizontal lines, and mechanism connected to said scoop for counter-balancing the downward tilting movement thereof.
24. A loading machine comprising a frame, a pair of arms carried by said frame, a scoop pivotally supported by said arms, mechanism mounted on one of said arms for swinging said scoop about its pivotal support, and counterbalancing mechanism for said scoop carried by the other of said arms.
25. A loading machine comprising a frame, a pair of arms on said frame, a scoop pivotally connected with said arms at a point adjacent said scoop, a motor connected with one of said arms and movable therewith for swinging said scoop about its pivotal support, counterbalancing mechanism for said scoop connected with the other of said arms, and means for moving said arms on said frame to advance said scoop into engagement with material to be loaded.
26. A loading machine comprising a main frame, a supplemental frame pivotal-

ly mounted on said main frame for lateral movement relative thereto, a pair of arms slidably carried by said supplemental frame, a scoop pivotally connected with said arms at a point adjacent said scoop, rack and pinion mechanism for advancing said arms on said supplemental frame to cause said scoop to engage material to be loaded, mechanism carried by one of said arms for tilting said scoop about its pivotal connection to discharge material from said scoop and for holding said scoop in fixed angular position relative to its pivotal support, a counterbalance for said scoop carried by the other of said arms, and an extensible conveyor mounted on said supplemental frame and having a portion thereof connected with arms adjacent the pivotal support for said scoop for receiving material discharged from said scoop when said scoop is tilted about its pivotal support.

27. A loading machine comprising a supporting frame, a scoop pivotally mounted on said frame with the turning axis of the scoop at the scoop itself, means for advancing said scoop relatively to said frame to gather a load of material, self-locking worm gearing for swinging said scoop about its turning axis to discharge material from said scoop, and counterbalancing mechanism for said scoop.

28. In a loading machine, the combination with a supporting frame, of a scoop pivotally connected thereto, means for tilting said scoop on its pivotal support, a counterbalance, and connections between said counterbalance and said scoop to hold said scoop down when in a predetermined position and tend to tilt said scoop upwardly when the latter is above another predetermined position.

29. In a loading machine, the combination with a supporting frame, of a scoop pivotally connected thereto, counterbalancing mechanism and connections between said counterbalancing mechanism and said scoop to cause said counterbalancing mechanism to hold said scoop down when below a predetermined position and tend to move said scoop up when the latter is above a predetermined position.

30. In a loading machine, the combination with a supporting frame, of a scoop, means for pivotally supporting said scoop and for supporting said scoop for movement rectilinearly to and from said frame while confining the turning axis of said scoop to a generally horizontal path, mechanism for moving said supporting means together with said scoop rectilinearly along horizontal lines, and adjustable supports at the outer end of said supporting means adjacent said scoop in position to engage the surface adjacent the material to be loaded to afford additional support for said supporting

means when the scoop is at the outer limits of its strokes.

31. In a loading machine, the combination with a supporting frame, of a scoop, a scoop supporting mechanism, means on said frame for confining said scoop supporting mechanism for movement relatively to said frame along horizontal lines, means for moving said scoop supporting mechanism forward to effect forward movement of said scoop along horizontal lines to gather a load, and a supplemental support connected to said scoop supporting mechanism to move therewith in position to engage the surface upon which the scoop is operable when the scoop is moved downward by the weight of the material therein.

32. A loading machine comprising a frame, an arm carried by said frame, means for advancing said arm relative to said frame, a scoop carried by said arm and movable therewith into engagement with material to be loaded, means for swinging said scoop upwardly to raise material engaged thereby, and a supplemental support connected with said arm to prevent excessive downward movement thereof under the weight of material in said scoop.

33. A loading machine comprising a supporting frame, a scoop, an auxiliary support for said scoop mounted on said frame for movement relatively thereto to enable said scoop to reach out and gather a load, means for moving said auxiliary support relatively to said frame to cause said scoop to gather a load, means for tilting said scoop up off the ground or floor in advance of said frame and said auxiliary support, and a supplemental support connected with said auxiliary support in position to engage the ground or floor to prevent excessive downward movement of said auxiliary support and said scoop when the latter is tilted upwardly with a load of material therein.

34. A loading machine comprising a support, an extensible frame mounted on said support and projecting forwardly therefrom, a scoop carried by said extensible frame, and a supplemental support connected with said frame adjacent said scoop and positioned normally a slight distance above the surface upon which said machine operates so that it will engage said surface to prevent excessive downward movement of said frame under the weight of material on said scoop.

35. A loading machine comprising a support, a frame carried by said support, arms slidably mounted on said frame, a scoop pivotally connected with said arms, means for advancing said arms relative to said frame to cause said scoop to engage material to be loaded, means for swinging said scoop upwardly about its pivotal connection while in engagement with said material, and

adjustable jacks carried by said arms adjacent said scoop for engaging the surface upon which said machine operates to prevent excessive downward movement of said arms under the weight of material upon said scoop.

36. A loading machine comprising a main frame, a supplemental frame pivotally mounted on said main frame to swing laterally relatively thereto, arms slidably mounted on said supplemental frame, a scoop having pivotal connections with said arms at a point adjacent said scoop, means for advancing said arms relative to said supplemental frame to cause said scoop to engage material to be loaded, means for swinging said supplemental frame and scoop laterally relative to said main frame, mechanism movable with said arms and scoop to tilt said scoop about its pivotal support to discharge material therefrom, counterbalancing mechanism movable with said arms and scoop to assist said tilting mechanism by counteracting the weight of said scoop, an extensible conveyor carried by said supplemental frame and having a portion thereof connected with said arms adjacent the pivotal support for said scoop for receiving material discharged from said scoop, and supplemental supports adjustably connected with said arms adjacent said scoop to prevent excessive downward movement of said arms under the weight of material on said scoop.

37. In loading apparatus, the combination with a main frame, of a supplemental frame with its rear end slidably along said main frame, an auxiliary frame mounted on said main frame and pivotally supporting the forward end of said supplemental frame, a scoop pivotally supported on said auxiliary frame adjacent the pivotal support of the forward end of said supplemental frame, an extensible conveyor on said main and supplemental frames with a portion always in a receiving position adjacent the rear end of said scoop, means for thrusting forward said auxiliary frame to cause said scoop to gather a load while said conveyor is extended with its receiving portion remaining in fixed relation with the rear end of said scoop, means for driving said conveyor, and mechanism for tilting said scoop to discharge the load therefrom out of the rear end thereof onto such receiving portion of said conveyor.

38. In loading apparatus, the combination with a truck frame provided with wheels adapted to travel on a mine track, of propelling mechanism connected to the wheels of said truck frame and depending upon frictional contact between the treads of said wheels and the rails of said track for propelling effect, a scoop, means for supporting said scoop for movement to and from said frame and in advance thereof, conveyor mechanism mounted longitudinally of said

- truck frame with its forward end in receiving position back of said scoop and in alignment therewith, means for anchoring said truck frame to the rails of said track and to the interior of the mine chamber, and additional propelling mechanism for said scoop comprising mechanism for moving said scoop-supporting-means relatively to said truck frame to advance said scoop to take a load against the resistance of said anchoring-means acting as abutment mechanism.
39. In loading apparatus, the combination with a wheel-mounted frame having a free and unobstructed space back of the same for the movement of mine cars on a mine track on which said frame is adapted to travel, of propelling mechanism connected to the wheels of said frame, means for controlling said propelling mechanism at will, conveyor mechanism mounted on said frame and extending longitudinally thereof from a receiving position at the forward end of said frame to a delivery position to a mine car back of said frame, a scoop, means for supporting said scoop for free and unobstructed movement in advance of said frame, abutment mechanism comprising means for anchoring said frame to the rails of said track independently of said wheels, additional propelling mechanism for said scoop comprising means for moving said scoop-supporting-means relatively to said frame to cause said scoop to gather a load against the resistance of said abutment mechanism, and means for controlling said additional propelling mechanism at will.
40. In a loading machine, the combination with a main frame, of a supplemental frame mounted on said main frame for arcuate movement relatively thereto on an upright axis, a scoop, mechanism on said scoop for supporting said supplemental frame while confining the turning axis of said scoop to a generally horizontal path of movement, mechanism for operating said scoop by moving the same relatively to said supplemental frame while the turning axis of said scoop is confined to said generally horizontal path of movement, and extensible conveyer mechanism on said main and supplemental frames with the receiving end in fixed relation to the delivery end of said scoop, the latter being in registry with said conveyer and movable in an arc therewith.
41. In a loading machine, the combination with a truck comprising wheels adapted to travel on a mine track, of brake mechanism applicable to the said wheels to prevent rotation thereon and thereby hold said truck in fixed position on said track, means connected to said truck in position to engage the rails separately from said wheels and anchor said truck by providing a rigid abutment against endwise movement of said truck along said track, shoveling mechanism mounted on one end of said truck and comprising a scoop, and means for operating said shoveling mechanism including movement of said scoop along lines parallel to said track to gather a load against the resistance exerted by said brake mechanism and by said rail anchoring mechanism.
42. In a loading machine, the combination with a truck having wheels adapted to travel on a mine track, of brake mechanism cooperating with said wheels to hold said truck in fixed position on said track, mine jack mechanism mounted on the truck frame in position to engage the track rails to anchor the truck independently of said brake mechanism against movement along said track in either direction, shoveling mechanism mounted on one end of said truck and comprising a scoop, and means for operating said shoveling mechanism by moving said scoop along lines approximately parallel to the mine floor to gather a load therefrom against the resistance of said brake mechanism and said mine jack mechanism.
43. In a loading machine, the combination with a truck having wheels adapted to travel on a mine track, of mine jack mechanism pivotally connected to the truck frame in position to engage a rail of the mine track and the interior of a mine chamber to form an abutment against movement of said truck along said track, shoveling mechanism connected to said truck and comprising a scoop movable to and from the truck, and means for operating said shoveling mechanism including outward movement of said scoop along lines substantially parallel to the mine floor to gather a load against the resistance exerted by such abutment.
44. In a loading machine, the combination with a truck having wheels adapted to travel on a mine track, of roof jack mechanism pivotally connected to the truck frame at a predetermined distance above the rails of the mine track and comprising a segment adapted to engage a rail of the track when such roof jack mechanism is swung to upright position, shoveling mechanism mounted on said truck and comprising a scoop movable outwardly from the truck along horizontal lines to gather a load, and means for operating said shoveling mechanism including such movement of said scoop against the resistance of said roof jack mechanism when the latter is applied to a rail of the mine track to form an abutment to prevent movement of a truck along the track.
45. A loading machine comprising a wheeled truck adapted to travel on a mine track, shoveling mechanism carried by said truck, and an extensible jack carried by said truck and having a foot piece movable into position to engage a rail of said mine track and an extensible member adapted to engage a wall of the mine chamber to anchor the

truck to the track during the operation of said shoveling mechanism.

46. A loading machine comprising a wheeled truck adapted to travel on a mine track, and a mine jack pivoted to said truck and having a foot piece adapted to be swung into engagement with a track rail for anchoring the loading machine to the track.

47. A loading machine comprising a wheeled truck, shoveling mechanism carried by said truck, and an abutment for the shoveling mechanism comprising a mine jack carried by the truck and having a foot piece movable into engagement with one of the rails of the track to receive the thrust of the jack when the latter is caused to engage a wall of the mine chamber.

48. A loading machine comprising a frame, track wheels on which said machine travels, a member pivotally connected with said frame and arranged to be moved into and out of engagement with one of said track rails, and an extensible jack connected with said member and arranged to engage a fixed abutment and to exert pressure upon said pivoted member to hold said frame in fixed position on said track rail.

49. A loading machine comprising a wheeled truck adapted to travel on a mine track, and an abutment comprising a shoe pivoted to the truck on an axis extending transversely of the track and a wall jack pivoted to the said shoe on an axis extending longitudinally of the track.

50. A loading machine comprising a frame, a track upon which said frame is arranged to travel, a member removably and pivotally connected with said frame and arranged to bear upon said track when in one position, an extensible jack pivotally connected with said member and having a contacting device for engaging a fixed abutment, and means for forcing said contact device against said abutment to hold said jack in place, the force exerted by said jack being transmitted through said pivoted member to said track.

51. In a loading machine, the combination with a supporting frame, of a scoop having a wide receiving mouth and a comparatively contracted discharge opening at its rear end, means for supporting said scoop pivotally at its rear end with the turning axis at such rear end confined to a generally horizontal path of movement, a conveyer on said frame with its receiving end in fixed relation of the rear end of said scoop so as always to be in position to receive material from the rear end of said scoop, means for moving said scoop supporting means bodily forward and rearward to secure bodily forward and rear movements of said scoop parallel to the length of the machine and relatively to said frame to gather a load with its wide open mouth, and mechanism for swinging the

front portion of said scoop on said rear axis to deliver its load rearwardly out of said contracted discharge opening to said receiving end of said conveyer.

52. In loading apparatus, the combination with a frame, of a scoop, conveyor mechanism mounted on said frame longitudinally thereof behind said scoop and in registry therewith, driving mechanism for moving the scoop forward and rearward with its receiving lip off the ground, mechanism for limiting the reciprocation of the rear portion of said scoop over an approximately horizontal path, and another driving mechanism for tilting the front portion of said scoop to cause material therein to slide out of the rear end thereof for delivery to said conveyor, said last-named driving mechanism comprising means for holding the scoop with its receiving lip in adjusted position above the surface over which it is moved during the scooping operation.

53. In loading apparatus, the combination with a scoop, of a mechanism for confining the rear portion of said scoop to movements in a generally horizontal direction and to turning movements, a laterally movable support for said scoop, an extensible conveyor on said support with a receiving portion always immediately back of said scoop in position to receive material from the latter in any forward position thereof, driving mechanism for moving the scoop forward and rearward by reciprocating the rear portion thereof in a general horizontal direction along said confining mechanism, another driving mechanism for tilting the forward portion of said scoop to effect the discharge of the load therein out of the rear end thereof on to said receiving portion of said extensible conveyor in any of the forward positions of said scoop, and means for operating the conveyor to move such material toward loading position.

54. In loading apparatus, the combination with a frame, of a scoop, an extensible conveyor on said frame always in position to receive material from said scoop in any of the positions of the latter, mechanism for confining the rear portion of said scoop to a rearward and forward movement over an approximately horizontal path, driving mechanism for moving said scoop bodily forward and rearward, additional driving mechanism for turning said scoop on an axis substantially at said path of reciprocation of the rear portion of said scoop to deliver material out of the rear end of said scoop onto said conveyor in any of the forward positions of said scoop, and means for controlling at will either of said driving mechanisms independently of the other.

55. A loading machine comprising a main frame, truck wheels for supporting said frame, a rearwardly extending discharge

- conveyor pivotally mounted on said frame to swing laterally, a forwardly extending supplemental frame pivotally mounted on said main frame for lateral movement, extensible conveyor mechanism carried by said supplemental frame, a scoop connected with said supplemental conveyor mechanism, means for advancing said scoop relative to said supplemental frame, and means for tilting said scoop upwardly to dump material therefrom onto said conveyor mechanism at various positions of advancement of said scoop.
56. A loading machine comprising truck wheels, a main frame mounted on said truck wheels and extending forwardly and rearwardly of said wheels, a discharge conveyor pivotally mounted on said main frame near the central portion thereof and having a sliding support located adjacent the rear portion of said frame, a supplemental frame pivotally mounted on said main frame adjacent said truck wheels and extending forwardly beyond said main frame, extensible conveyor mechanism carried by said supplemental frame and arranged to discharge material into said discharge conveyor, a scoop carried by said supplemental frame at the forward end of said extensible conveyor mechanism, means for advancing said scoop relative to said main frame to cause said scoop to engage material to be loaded, means for swinging said scoop laterally relative to said main frame, and means for tilting said scoop upwardly to discharge material therefrom onto said extensible conveyor mechanism at various advance positions of said scoop.
57. In a loading machine, the combination with a main frame, of a supplemental frame pivotally mounted on said main frame for arcuate movement relatively thereto on an upright axis, means comprising self-locking worm gearing for swinging said supplemental frame laterally on such upright axis relatively to said main frame and locking said supplemental frame in adjusted position, a scoop, extensible supporting mechanism for carrying said scoop on said supplemental frame for forward and backward movements relatively to said supplemental frame in the various arcuate positions of the latter, an extensible conveyor mounted on said supplemental frame and having a forward receiving end in fixed relation to said scoop in the various advanced positions thereof and means for tilting said scoop to discharge material therefrom onto said conveyor at any of the positions of said scoop in advance of said supplemental frame.
58. In a loading machine, the combination with a truck frame having wheels adapted to travel on a mine track, of a supplemental frame pivotally mounted on said truck frame for lateral movement relatively thereto, a rearward extending discharge conveyor pivotally mounted on said truck frame for lateral movement relatively thereto, an extensible conveyor on said supplemental frame in delivery communication with said discharge conveyor, a pair of arms slidably mounted on said supplemental frame, a scoop pivotally connected to said arms, means for advancing and retracting said arms relatively to said supplemental frame to advance and retract said scoop, mechanism comprising worm gearing for tilting said scoop to deliver material to said extensible conveyor at any of the forward positions of said scoop, counterbalancing mechanism for said scoop, supplemental supports connected to the forward ends of said arms in position to rest on the ground to assist in supporting the scoop and its load when said scoop is tilted upwardly in a forward position thereof, propelling mechanism to move the whole machine along the track to cause said scoop to gather a load, brake mechanism to hold the truck wheels against turning when said scoop is advanced by moving said arms forward and anchoring mechanism carried by said truck frame in position to engage the rails of the track independently of the truck wheels to form abutment mechanism to resist movement of the machine along the track when said scoop is operated for delivering loads approaching the maximum capacity of said scoop.
59. In a loading machine, the combination with a scoop, of mechanism for pivotally supporting said scoop, supporting framework, guide-ways in said framework for confining the turning axis of said scoop to a generally horizontal path of movement, extensible conveyor mechanism on said framework behind and always near the scoop in the various positions of the latter, and means for imparting to the forward portion of the scoop an upright movement and to the rear portion an approximately reciprocatory relatively to said framework, such means causing the forward portion of said scoop to go forward low enough to gather a load and such means causing said scoop to be turned on its rear pivoted portion to discharge the load backward therefrom for delivery onto the top of the receiving end of said extensible conveyor mechanism at the various forward positions of said scoop.
60. In a loading machine, the combination with spaced-apart guide-ways extending forwardly and rearwardly, of an endless belt conveyor between said guideways, slide-blocks confined in said guide-ways, a scoop pivotally connected to the forward ends of said slide-blocks at the rear portion of said scoop, means for reciprocating said slide-block in a general horizontal direction, means connected to said slide-blocks to extend said con-

veyor forwardly when said slide-blocks are moved forwardly and to maintain a portion of said conveyor in position to receive material from said scoop in the various forward positions of the latter, and mechanism for turning said scoop to discharge the contents thereof onto said conveyor in any of the forward positions of said scoop.

61. In a loading machine, the combination 10 with a supporting frame having spaced-apart guide-ways extending forward and rearward, of slide-blocks confined in said guideways, a scoop pivotally connected at its rear portion to the forward portions of 15 said slide-blocks, a supplemental frame pivotally connected to said slide-blocks near the turning axis of said scoop and having its rear end movable along said supporting frame, means for moving said slide-blocks 20 in a general horizontal direction, an endless belt conveyor mounted on said main and supplemental frames and extensible forwardly when said slide-blocks are moved forwardly, and mechanism for turning the 25 scoop to discharge material therefrom onto said conveyor in any positions of the scoop in advance of said supporting frame.

62. In a loading machine, the combination 20 with a main frame, of a supplemental frame pivotally connected to said main frame for lateral movement relatively thereto, a scoop mounted on said supplemental frame and extensible in advance thereof, means for reciprocating said scoop to reach forward for 25 loads in various arcuate positions, a chute back of said scoop and in alinement therewith, and means comprising an endless conveyor for transferring material in said scoop out of the rear end thereof into the forward 40 end of said chute and along the latter toward loading position.

63. In a loading machine, the combination 45 with supporting framework, of a scoop mounted thereon and extensible in advance thereof, a chute back of said scoop and in alinement therewith, mechanism for forcing the scoop into the material to be loaded, and mechanism comprising an endless conveyor traveling along said scoop relatively thereto 50 for transferring material out of the open rear end of said scoop into the forward open end of said chute and along the latter toward loading position.

64. A loading machine comprising a 55 frame, a pair of arms carried by said frame, a scoop pivotally connected to said arms, mechanism for tilting said scoop about its pivotal support, and counterbalancing mechanism for said scoop.

65. A loading machine comprising a 60 frame, a pair of arms on said frame, a scoop pivotally connected to said arms, means for moving said arms relatively to said frame to advance said scoop into engagement with material to be loaded, means for swinging

said scoop about its pivotal support, and counterbalancing mechanism for said scoop.

66. A loading machine comprising a main frame, a supplemental frame pivotally mounted on said main frame for lateral 70 movement relative thereto, a pair of arms slidably carried by said supplemental frame, a scoop pivotally connected to said arms, means for advancing said arms to cause said scoop to engage material to be loaded, 75 mechanism for tilting said scoop and for holding said scoop in fixed angular position relative to its pivotal support, a counterbalance for said scoop and an extensible conveyor mounted on said supplemental frame 80 and having a portion thereof connected with said arms in position for receiving material from said scoop when the latter is tilted upward sufficiently on its pivotal support.

67. A loading machine comprising a 85 frame, a scoop pivotally mounted thereon, means for advancing said scoop to engage material to be loaded, a self-locking worm drive for swinging said scoop about its pivotal support, and counterbalancing 90 mechanism for said scoop.

68. A loading machine comprising supporting framework, arms slidably connected thereto, a scoop pivotally connected to said arms, means for moving said arms relatively to said framework for advancing said scoop to gather a load of loose material, means for tilting said scoop upwardly on its pivotal support, and means carried by the 95 said arms in position to engage the surface 100 on which said machine operates to limit the downward movement of the outer ends of said arms under the weight of said scoop and the material therein and thereby assist said arms in supporting the load.

69. A loading machine comprising supporting framework, arms slidably mounted thereon, a scoop pivotally connected to said arms, means for moving said arms to advance said scoop to gather a load, means for tilting said scoop, counterbalancing mechanism for said scoop, an extensible conveyor having a portion thereof connected to said arms in position to receive material from said scoop, and supplemental supports connected to said arms to limit the downward movement thereof under the weight of the 110 material in said scoop.

70. A loading machine comprising a 115 wheeled truck adapted to travel on a mine track, and abutment mechanism carried by said truck in position to be moved into engagement with one of the rails of the mine track and into engagement with the interior of a mine chamber while remaining connected to said truck.

71. A loading machine comprising a 120 wheeled truck adapted to travel on a mine track, and abutment mechanism comprising 125 a shoe movable into position to engage a rail

of the track and an extensible jack connected to said shoe and to said truck and movable into position against the wall of a mine chamber to force said shoe against the rail and anchor said truck to the track.

72. In a loading machine, the combination with a supporting frame, of a scoop pivoted on the forward end of said frame for up and down movement relatively thereto,

10 an endless traveling conveyer extending from the extreme forward end of said scoop horizontally rearwardly a predetermined distance and then upwardly on an incline along said frame toward loading position, means

15 for adjusting the elevation of said scoop together with the horizontal portion of said endless traveling conveyer, and means for operating said conveyer along said scoop as well as along said frame to transfer material from said scoop toward loading position at the various adjusted elevations of said scoop.

73. In a loading machine, the combination with a supporting frame, of a flexible scooping section at the forward end of said frame with a free and unobstructed space in advance of such scooping section, an endless conveyer extending from the extreme forward end of said scooping section horizontally along the latter a predetermined distance, means for moving said scoop forwardly to gather a load for removal by said endless conveyer, and means for tilting the scooping section upwardly relatively to said supporting frame to facilitate removal of the material from such scooping section toward loading position.

74. In a shoveling machine, the combination with a supporting frame, of a scoop pivoted to the forward end of said frame, an endless conveyer extending from the extreme forward end of said scoop rearwardly horizontally a predetermined distance and then upwardly on an incline over the pivotal connection between said scoop and said frame and along the latter toward loading position, means for propelling said frame to effect forward movement of said scoop into engagement with the material to be handled,

45 and self-contained power-operated mechanism for tilting said scoop upwardly relatively to said frame to facilitate the handling of material on said scoop by means of said endless conveyer.

55 75. In a shoveling machine, the combination with a supporting frame, of a scoop pivoted on the forward end thereof for adjustment up and down on a horizontal axis, an endless conveyer having superposed portions

60 traveling to and from the extreme forward end of said scoop and horizontally a predetermined distance back of the said extreme forward end, means between said scoop and said frame for tilting the scoop upwardly together with that portion of the endless

conveyer carried thereby, mechanism for propelling said frame and said scoop to force the latter under the material to be loaded, and means for operating said conveyer including the horizontally traveling portion thereof to loosen the material and remove it toward loading position as gathered by the scoop.

76. In loading apparatus, the combination with a supporting frame, of a conveyer trough extending along said supporting frame, a supplemental conveyer trough pivoted at the forward end of said first-named conveyer trough, a scoop at the forward end of said supplemental conveyer trough, an endless conveyer extending from the extreme forward end of said scoop horizontally along the latter and thence along both of the aforesaid conveyer troughs toward loading position, means for moving said scoop to gather a load of material directly onto the forward end of said conveyer, means for operating said conveyer, and means for tilting said supplemental conveyer trough upwardly after such loaded material has been gathered by said scoop.

77. In loading apparatus, the combination with a supporting frame, of a scoop pivoted for up and down movement on the forward end of said frame and provided with a forward substantially horizontal portion for engagement with the material to be loaded, an endless conveyer extending from the extreme forward end of said scoop horizontally along the horizontal portion of said scoop and thence toward loading position, means for operating said scoop to gather a load of material by moving the scoop bodily with the forward portion of said conveyer, and means for tilting said scoop upwardly to adjust the elevation thereof for its scooping operation and to assist the operation of said conveyer when tilted to a higher position.

78. In loading apparatus, the combination with a supporting frame, of a scoop pivoted thereto for up and down movement, the space in advance of said scoop being free and unobstructed, an endless conveyer extending from the extreme outer end of said scoop and substantially horizontally along the forward end portion of said scoop and thence upwardly on an incline toward loading position, means for operating said scoop to gather a load from a pile of coal as left in a mine after being blasted from a mine vein, means for operating said endless conveyer to loosen the material and remove the same, and self-contained power-operated mechanism for tilting said scoop relatively to said frame to vary the elevation of the outer end of said scoop together with the outer end portion of the conveyer.

79. In loading apparatus, the combination with a truck adapted to travel on a mine

- track, of a supporting frame mounted on said truck, a scoop pivotally connected to the forward end of said supporting frame for adjustment in elevation and having the forward horizontal portion adapted to be let down for operation horizontally over the mine floor in advance of the mine track, means for propelling said truck along said mine track to effect horizontal operation of said scoop over the mine floor in advance of said track to gather a load of material, conveyer mechanism extending rearwardly from the extreme front end of said scoop horizontally along the horizontal portion of said scoop and thence toward loading position to transfer gathered material rearwardly from the horizontal portion of said scoop, and self-contained power-operated mechanism for varying the elevation of said scoop.
80. In loading apparatus, the combination with a wheeled truck adapted to travel on a mine track, of a supporting frame mounted thereon for movement therewith, a scoop pivoted to the forward end of said supporting frame and having a forward horizontal extension for movement horizontally over the mine floor, means for propelling said truck along the track to effect the operation of said scoop horizontally over the floor in advance of said track, conveyer mechanism extending rearwardly from the forward end of said horizontal portion of said scoop in position to act directly on the material while in the scoop to loosen the material and move it from the scoop along said frame toward loading position, and self-contained power-operated mechanism for tilting said scoop relatively to said frame without interfering with the operation of said conveyer mechanism.
81. In a track mounted loading machine, the combination with a wheeled truck, of a supporting frame mounted thereon, anchoring mechanism connected to said supporting frame and adapted to engage the rails of said track and the roof of the mine chamber to form abutments for said loading machine, shoveling mechanism comprising a scoop and extensible supporting mechanism therefor mounted on said supporting frame, means for thrusting said scoop forward in advance of the track on which said wheeled truck is mounted while said anchoring mechanism acts as an abutment against rearward movement of said supporting frame, and conveyer mechanism extensible in harmony with said extensible supporting mechanism and operable continuously during such gathering operation of said scoop to remove the gathered material toward loading position in the various advanced and retracted positions of said scoop relative to said supporting frame.
82. In loading apparatus, the combination with a scoop, of supporting mechanism im-
- movably secured to said scoop rearward of its front end, the forward portion of said scoop being substantially horizontal for horizontal movement over the mine floor under the material to be loaded, power driven means comprising a worm gear connected rigidly to said scoop by means of said supporting mechanism to transmit powerful turning movements to said supporting mechanism to effect arcuate turning movements of the forward portion of said scoop, conveyer mechanism extending rearwardly from the extreme forward end of said scoop, and a supporting frame for carrying the aforesaid parts in cooperative relation.
83. In loading apparatus, the combination with a scoop, of supporting mechanism immovably secured to said scoop rearward of its front end, power driven means comprising a worm gear connected directly to said scoop by being rigidly connected to said supporting mechanism to transmit turning movements to said supporting mechanism to effect arcuate turning movement to the forward portion of said scoop, a supporting frame, conveyer mechanism extending from the extreme forward end of said scoop rearwardly along said supporting frame, means for moving said scoop to various positions in advance of said supporting frame to gather loads of material, and means for operating the said conveyer mechanism during the gathering operations to loosen the material and convey it rearwardly toward loading position.
84. In a loading machine, the combination with a frame, of guideways extending longitudinally of said frame, slide blocks confined in said guideways, a scoop pivoted directly to said slide blocks at its rear end portion, mechanism for moving said slide blocks forward and backward to cause said scoop to gather successive loads, means comprising a worm gear rigidly connected to said scoop to turn the latter relatively to said blocks and thereby vary the elevation of the forward end of said scoop, and traveling conveyer mechanism extending from said scoop rearwardly along said frame and adapted for transferring material rearwardly from said scoop irrespective of the elevation of the latter.
85. In a loading machine, the combination with a supporting frame, of a scoop pivotally connected to said frame for up and down movements, said scoop having a forward substantially horizontal gathering portion, means for advancing said scoop to gather a load of material, mechanism comprising worm gearing rigidly connected to said scoop for powerfully swinging the latter about its pivotal connection to said frame to tilt said scoop upwardly to loosen the material to be loaded, and a traveling conveyer extending rearwardly from the horizontal

portion of the scoop beyond its pivotal connection to said frame.

86. In a loading machine, the combination with a supporting frame, of a scoop, turnable supporting mechanism for said scoop, power driven means comprising locking worm gearing connected to said turnable supporting mechanism for tilting said scoop and locking it in adjusted position, means for connecting said turnable supporting mechanism to said frame for movement relatively thereto while confining the turning axis of said scoop to a generally horizontal path of movement, and means for advancing said scoop relatively to said frame to gather a load while said locking worm gearing holds said scoop fixed in adjusted position and while the turning axis of said scoop is confined to such horizontal path of movement.

87. In a loading machine, the combination with a supporting frame, of a scoop having a turning axis confined to a position along general horizontal directions, traveling conveyer mechanism mounted on said frame, means for moving said scoop bodily forward and rearward relatively to said frame and parallel to the length of the machine by remaining in front of said conveyer mechanism, mechanism comprising locking worm gearing connected directly to said scoop for tilting the latter upwardly and locking it in adjusted position and for lowering said scoop by positively moving it and preventing it from dropping by gravity, and means for operating said conveyer mechanism.

88. In loading apparatus, the combination with an elongated main frame, of truck wheels for supporting said main frame, a rearwardly extending discharge conveyer mounted on one portion of said main frame, a forwardly extending supplemental frame mounted on another portion of said main frame, a scoop pivoted to the forward end portion of said supplemental frame, self-contained power-operated mechanism for tilting said scoop to adjust its elevation, means for advancing and retracting the scoop for the purpose of gathering loads, and extensible traveling conveyer mechanism between said scoop and said discharge conveyer to maintain transfer communication between said scoop and said discharge conveyer for the various advanced and retracted positions of said scoop.

89. In loading apparatus, the combination with a supporting frame, of a scoop confined to positions always in front of said frame, reciprocal supporting mechanism on said frame, a pivotal connection between said scoop and said supporting mechanism, means for reciprocating said supporting mechanism to secure horizontal forward and rearward movements of said scoop, means for independently controlling said forward and rear-

ward movements, mechanism comprising a worm gear rigidly connected to said scoop to positively lift and to positively lower such scoop to prevent its dropping by gravity, and conveyer mechanism maintained in communication with said scoop and the loading position of the machine for the various advanced positions of said scoop.

90. In loading apparatus, the combination with a main frame, of a supplemental frame pivoted to said main frame for movement to lateral positions relative thereto, a scoop carried by said supplemental frame and movable laterally therewith, means for reciprocating said scoop relatively to said supplemental frame to cause said scoop to gather loads of material, and mechanism comprising worm gearing connected directly to said scoop for positively tilting the latter upwardly and for positively moving it downwardly to prevent it from being dropped by gravity.

91. In loading apparatus, the combination with supporting framework, of a scoop pivotally connected to said framework with a turning axis confined for movement along a generally horizontal path of travel, mechanism comprising a worm gear connected directly to said scoop for positively tilting the latter on such axis both upwardly and downwardly to adjust the elevation of said scoop and to prevent the latter from dropping by gravity, and means for operating said scoop by advancing the same to gather a load after said worm gear has moved the scoop down to a predetermined position.

92. In loading apparatus, the combination with supporting framework, of supplemental supporting mechanism confined in said framework to movements in general horizontal directions, a scoop pivotally connected to said supplemental supporting mechanism to have a turning axis confined to a generally horizontal path of travel, means for moving said supplemental supporting mechanism relatively to said framework to cause said scoop to move horizontally to gather a load, and means comprising a worm gear connected to said scoop for moving the latter upwardly to adjust its elevation and for moving the scoop downwardly to prevent its being dropped by gravity.

93. In loading apparatus, the combination with a main frame, of a supplemental frame mounted on said main frame for horizontal advanced and retracted movements relatively thereto, a scoop pivotally connected to said supplemental frame for up and down movements on a horizontal axis, means for advancing and retracting said supplemental frame to reciprocate said scoop, and mechanism comprising locking worm gearing connected to said scoop for tilting the latter upwardly on its horizontal

- axis after gathering a load and for locking the scoop at adjusted elevation during the retraction of the scoop and for moving the scoop down positively to prevent its being dropped by gravity preparatory to another advancing gathering operation.
94. In loading apparatus, the combination with a supporting frame, of a scoop pivotally connected thereto for tilting movement on a horizontal axis, means for effecting advancing and retracting movements of said scoop for load gathering operations, and mechanism comprising locking worm gearing connected to said scoop for tilting the latter upwardly after gathering a load and for positively moving the scoop down while preventing the same from dropping by gravity preparatory to another advancing gathering movement.
95. In loading apparatus, the combination with a supporting frame, of a scoop pivotally mounted on said frame and for movement beyond the same, means comprising self-locking worm gearing connected directly to said scoop for tilting the latter upwardly and for positively moving the scoop down to prevent its dropping by gravity and for holding the scoop in gathering position at the surface from which the material is to be loaded, and means for reciprocating said scoop rectilinearly and substantially parallel to the plane of said surface while held in gathering position at such surface by said worm gearing, to cause said scoop to reach out from said supporting frame to gather a load of loose material and carry it back toward said supporting frame.
96. In loading apparatus, the combination with a supporting frame, of a pair of arms slidably mounted on said frame for movement horizontally longitudinally of the frame, a scoop pivotally connected to said arms for tilting movements relatively thereto on a horizontal axis, means for moving said arms to advance said scoop to gather a load, and extensible conveyer mechanism for maintaining transferring communication between said scoop and a predetermined loading position at the rear portion of said frame for the various advanced positions of said scoop relative to said frame.
97. In loading apparatus, the combination with a supporting frame, of a scoop pivotally connected to said frame for up and down tilting movements on a horizontal axis confined to a generally horizontal path of travel, and mechanism comprising worm gearing for positively lifting said scoop to a position where material gathered therein will slide out of the rear end thereof and for positively moving the scoop down to prevent its dropping by gravity preparatory to a gathering operation, and means for operating the scoop to gather a load.
98. In loading apparatus, the combination with supporting framework, of a scoop pivoted thereto on a horizontal axis confined to a generally horizontal path of travel, means for advancing and retracting the scoop relatively to said frame for the purpose of effecting a gathering operation, and mechanism comprising worm gearing for tilting the scoop upwardly on such horizontal axis to discharge gathered material out of the rear end thereof and for positively moving the scoop down to prevent its being dropped by gravity preparatory to advancing said scoop for another gathering operation.
99. In loading apparatus, the combination with a supporting frame, of a scoop pivotally connected thereto, means for operating said scoop by causing the same to reach out from said frame to gather a load, a traveling conveyer, and means for tilting said scoop in any of its advanced positions while said conveyer remains in receiving communication with said scoop for all advanced positions of said scoop.
100. In loading apparatus, the combination with a wheeled truck adapted to travel on a mine track, of gathering mechanism mounted on said truck for operation along the floor in advance of the mine track, a loading conveyer mounted on said truck, a frame pivoted to said truck on an upright axis for carrying said loading conveyer and having a deep storage hopper the bottom of which is adjacent the plane extending through the tops of the wheels of the trucks, and conveyer apparatus between said gathering mechanism and deep storage hopper for delivering material from the gathering mechanism to said hopper in the various positions to which said frame is swung on its upright axis relatively to said truck.
101. In loading apparatus, the combination with a main frame, of a main conveyor mounted thereon in fixed relation thereto and having a rear elevated delivery position, a swinging supplemental conveyor having a forward relatively low receiving position and a rear elevated delivery position, said supplemental conveyor being mounted on said main frame and comprising a supplemental frame movable laterally on an upright axis and relatively to said main frame, a deep storage hopper connected to said supplemental frame in position to direct material from said main conveyor onto the receiving end of said supplemental conveyor at the bottom of the hopper throughout the range of lateral movement of said supplemental conveyor on said upright axis, a pivotal connection between the lower portion of said supplemental frame and said main frame, and an additional pivotal connection between the upper portion of said supplemental

frame and said main frame to provide a free and unobstructed space above the receiving end of said supplemental conveyor.

102. In loading apparatus, the combination with a main frame, of a swinging conveyor, a hopper for said conveyor, a U-shaped frame connected to said main frame and extending horizontally and rearwardly therefrom to afford a free and unobstructed space for the delivery of material into said hopper, and pivotal connections between said swinging conveyor and said main frame and comprising an upper pivotal connection to said U-shaped frame to support the overhanging weight of the rear portion of said swinging conveyor while permitting swinging movement of the latter on the upright axis extending through said pivotal connections.
103. In loading apparatus, the combination with a main frame, of a supplemental frame having a lower pivotal connection between the same and the rear lower portion of said main frame, a horizontal U-shaped frame extending rearwardly from the upper portion of said main frame and providing an opening for the delivery of material therethrough, a supplemental conveyor on said supplemental frame, a main conveyor on said main frame in position to deliver material through the opening in said U-shaped frame to said supplemental conveyor, a pivotal connection between said supplemental frame and said U-shaped frame and located substantially in vertical alinement with said first-named pivotal connection to afford an upright axis of swinging movement of said supplemental frame relatively to said main frame, and means for operating said conveyor.
104. In loading apparatus, the combination with a main frame, of a main conveyor mounted thereon, a supplemental frame mounted at the rear portion of said main frame to swing relatively thereto on an upright axis, said supplemental frame having an upward rearward extension adapted to overhang a mine car, a supplemental conveyor mounted on said supplemental frame in position to receive material from said main conveyor, a pivotal connection between said supplemental frame and said main frame below the receiving end of said supplemental conveyor, two horizontal supports one extending rearwardly from said main frame and the other extending forwardly from the upper intermediate portion of said supplemental frame, and a pivotal connection between said supports in vertical alinement with the lower pivotal connection to afford swinging of said supplemental frame on an upright axis extending through said pivotal connections while the overhanging portion of said supplemental frame is held in position by said supports.

105. In a loading apparatus, the combination with a main frame, of a main conveyer mounted thereon, a supplemental frame mounted on said main frame to swing laterally relatively thereto on an upright axis, a supplemental conveyer on said supplemental frame, a pivotal connection between the lower portion of said supplemental frame, a pivotal connection between the lower portion of said supplemental frame and said main frame, a supporting arm extending forward from the upper intermediate portion of said supplemental frame, a horizontal U-shaped support extending rearwardly from the upper rear portion of said main frame, and an additional pivotal connection between said forwardly extending arm and said rearwardly extending support to afford an upright axis for swinging movement of said supplemental conveyer while delivery communication is maintained between said main and supplemental conveyers and while the space above the receiving end of said supplemental conveyer remains free and unobstructed for the delivery of material from said main conveyer to said supplemental conveyer for the various angular positions of the latter relative to said main frame.

106. In loading apparatus, the combination with a main frame, of a main conveyer mounted thereon, of a supplemental frame having a rearward extension adapted to overhang a mine car, a supplemental conveyer mounted on said supplemental frame, a horizontal U-shaped frame extending rearwardly from the upper rear portion of said main frame to afford an unobstructed space for the passage of material from said main conveyer to said supplemental conveyer, a pivotal support between the lower forward portion of said supplemental frame and the rear lower portion of said main frame, a forwardly extending arm connected to the upper intermediate portion of said supplemental frame, and a pivotal connection between said arm and said U-shaped frame to co-act with said pivotal support to afford an upright axis for swinging movement of said supplemental conveyer relatively to said main conveyer.

107. In loading apparatus, the combination with a main frame, of a main conveyer mounted thereon, a supplemental frame having a lower pivotal connection between its forward portion and the rear portion of said main frame, a supplemental conveyer mounted on said supplemental frame, a hopper for directing material from said main conveyer onto said supplemental conveyer, a horizontal rearwardly extending U-shaped frame mounted on the upper portion of said main frame to provide an open space for the passage of material from said main conveyer into said hopper, and a pivotal connection between said supplemental frame

and said U-shaped frame in substantial vertical alinement with said first-named pivotal connection to afford an upright axis of swinging movement of said supplemental 5 conveyer relatively to said main frame.

108. In combination with a loading machine having a truck, digging and conveying mechanism supported thereby to swing laterally thereof, of means for supporting 10 the front of the machine wholly or partially independently of the truck wheels, comprising jacks on the truck body and having ground engaging portions.

109. In a loading machine, a truck, digging and conveying mechanism supported thereby to swing laterally thereof, and means for supporting the front part of the machine independently of the truck wheels, comprising a pair of jacks on the truck body 20 and having ground engaging portions beyond the front end of the truck.

110. In a loading machine, a truck, digging and conveying mechanism supported thereby to swing laterally thereon, and means for supporting the front part of the machine independently of the truck wheels, comprising a pair of jacks on the truck body, each jack comprising a member with a low ground engaging portion adapted to engage the ground forwardly of the truck.

111. In a loading machine, a truck, digging and conveying mechanism supported thereby to swing laterally thereon, and means for supporting the front part of the machine independently of the truck wheels, comprising a pair of jacks on the truck body, each having a ground engaging portion adapted to engage the ground forwardly of the truck, and means for adjusting the positions of the ground engaging portions of said jacks.

112. In a loading machine, a truck, digging and conveying mechanism supported thereby, and means for supporting the front part of the machine independently of the truck wheels, comprising a pair of jacks on the truck body and each having a ground engaging portion adapted to engage the ground forwardly of the truck, and means for adjusting the positions of the ground engaging portions of said jacks.

113. In a loading machine, the combination with a truck adapted to travel on a mine track, of digging and conveying mechanism supported by said truck for operation in advance of said mine track, means for supporting the front part of the machine independently of the truck wheels, comprising a pair of jacks on the truck body and each having a ground engaging portion adapted to engage the ground in advance of the mine track, and means for adjusting the positions of said ground engaging portions of said jacks.

114. In combination with a loading ma-

chine comprising a truck adapted to travel on a mine track with digging and conveying mechanism supported on said truck in position for operation in advance of the mine track, of a pair of jacks on the truck body 70 and in advance of the truck and each including a ground engaging portion for sliding over the ground in advance of the mine track.

115. In a loading machine, the combination with a truck adapted to travel on a mine track, of loading apparatus comprising a gathering device adapted to move over the floor in advance of the mine track, and means on the truck adjustable to floor engaging 80 positions in advance of the mine track to support the front part of the machine on such floor during the operation of said loading apparatus.

116. In a loading machine, the combination with material-handling mechanism comprising forwardly extending gathering means, a frame for supporting said gathering means for adjustment in elevation, mechanism between said supporting frame 90 and said gathering means for adjusting the elevation of the latter and for positively holding said gathering means at adjusted elevation, means for moving said gathering means laterally while being held at adjusted elevation, and means for moving the gathering means forward to operate the same to gather a load.

117. In a loading machine, the combination with an elongated supporting frame 100 having a rearwardly extending pivoted section adapted to overhang a mine car, of an endless conveyer having superposed portions traveling in opposite directions extending from a forward receiving position on said 105 supporting frame to the rear end of said pivoted extension, and means adjacent the pivot of said extension for engaging the lower run of said conveyer for driving the latter and holding taut the under run traveling along said extension.

118. In a loading machine, the combination with a supporting frame, of endless conveyer mechanism mounted on said frame, a supplemental frame pivoted to said supporting frame and extending rearwardly therefrom to support the rear portion of said endless conveyer, rotatable driving mechanism mounted on an axis below the pivotal connection of said supplemental frame to said 115 supporting frame in position to engage the lower run of said conveyer mechanism to hold the latter taut when driven, and means for actuating said driving means to operate said endless conveyer and hold taut those 120 portions thereof extending along said supplemental frame.

119. In loading apparatus, the combination with a wheeled truck adapted to travel on a mine track, of gathering mechanism 125

connected to said truck and adapted to extend beyond the mine track, a rear delivery conveyor mounted on said truck, and means connecting the upper portion of said delivery conveyor to said gathering mechanism forwardly of said truck to support said gathering mechanism for freedom of operation beyond the forward end of said track.

120. In loading apparatus, the combination with a truck adapted to travel on a mine track, of gathering mechanism comprising a scoop and conveyor connected to said truck to extend forwardly therefrom for operation over the floor and in advance of the mine track, a delivery conveyor mounted on said truck and comprising a conveyor frame, and supporting connections between the sides of said gathering mechanism forwardly of said truck and the upper portion of said frame.

121. In loading apparatus, the combination with a truck, of gathering mechanism, a loading conveyor, and supporting connections between the sides of said gathering mechanism and said loading conveyor.

122. In loading apparatus, the combination with a truck, of gathering mechanism extending forwardly from said truck, a loading conveyor extending rearwardly from said truck, and supporting connections comprising tie rods between the sides of said gathering mechanism and the upper portion of said loading conveyor so that the rearwardly extending portion of the latter tends to counter-balance the forwardly extending gathering mechanism.

123. In a loading machine, the combination with a supporting frame, of gathering mechanism pivoted thereto for lateral swinging movement relatively thereto on an upright axis, and a loading conveyor having a deep storage hopper with its bottom in a low position pivoted to said frame on the said upright axis for lateral swinging movement relatively to said frame while said gathering mechanism in its various angular positions remains in delivery communication with said hopper.

124. In a loading machine, the combination with a supporting frame, of gathering mechanism pivoted thereto for lateral swinging movement relatively thereto, a deep storage hopper pivoted to said frame on the said upright axis for lateral swinging movement relatively to said frame, and a pivotal connection between said gathering mechanism and said conveyor above the pivot to said frame.

125. In loading apparatus, the combination with a frame having wheels adapted to travel on a mine track, of gathering mechanism pivoted to said frame adjacent the track on which the machine travels, and a loading conveyor having a deep storage hopper with its bottom pivoted on the upright axis of the first named pivot and locating the bottom of the hopper adjacent the mine track.

In testimony whereof I have signed my name to this specification, on this 13th day of December, A. D. 1917.

EDMUND C. MORGAN.
